DESIGN FOR A SWING

Harry Sebel, London, England

Application May 16, 1946, Serial No. 129,762
In Great Britain March 27, 1945

Term of patent 14 years

(Cl. D34—5)

To all whom it may concern:

Be it known that I, Harry Sebel, a subject of the King of Great Britain, residing at 13 Kinloss Gardens, London N. 3., England, have invented a new, original, and ornamental Design for a Swing, of which the following is a specification, reference being had to the accompanying drawing, forming part thereof.

The figure is a perspective view of a swing showing my new design.

I claim:

The ornamental design for a swing, as shown.
HARRY SEBEL.
